B.P. McKinley

By his Attorney John O. Leffert

UNITED STATES PATENT OFFICE

BENJAMIN P. MCKINLEY, OF BROOKLYN, NEW YORK, ASSIGNOR TO THE BEYANT ELECTRIC COMPANY, A CORPORATION OF CONNECTICUT

COMBINED LAMP SOCKET CLUSTER AND CONNECTION PLUG

Application filed December 14, 1921. Serial No. 522,280.

This invention relates to lamp socket clusters having connected thereto a plug or adaptor whereby to connect one or more electric translating devices to a single cut-out 5 in an electric circuit, and it is the object of the invention to provide lamp socket clusters of this character in which the plug is separately connected to the lamp sockets, and further to improve the general construction and arrangement of lamp socket clusters of this 10 character to reduce the cost and facilitate the manufacture thereof, and to provide a socket cluster which is novel and pleasing in appearance.

Another object of the invention is to provide a lamp socket cluster of this character in which the lamp receiving shells are encased and surrounded by a one piece molded insulating material constructed and arranged for the securing of electric connection plugs 20 thereto of various forms with the electrical connections between the plug and contacts of the sockets enclosed in said material, and to arrange said insulating material at the outer 25 ends of the socket shells for the attachment and supporting of shades therefrom.

It is a further object of the invention to provide a lamp socket cluster of this character in which the insulating and encasing 30 material of the lamp sockets is molded with a recess therein arranged by the securing of the plug thereto to provide a closed chamber, with means arranged in said chamber to place one of the lamp sockets into and out of electrical connection with the other lamp socket 35 and plug.

In the drawings accompanying and forming a part of this specification, Figure 1 is a side elevation of my improved combined 40 lamp socket cluster and connection plug.

Figure 2 is a longitudinal sectional view.

Figure 3 is a sectional view taken on the lines 3—3 of Figure 2.

Figure 4 is a perspective view of the connection plug and showing the means to secure the same to the lamp socket encasing material.

Figure 5 is a perspective view of the lamp sockets with the integral insulating material 50 molded around the same and to show the ar-

rangement for the connection of the connection plug thereto.

Figure 6 is a perspective view of a pair of lamp receiving shells and showing the manner of electrically connecting the same. 55

Figure 6^a is a perspective view of one of the end contacts of a lamp socket.

Figure 7 is a side elevation, partly in section, of the lamp socket member with the plug attached and showing the means for placing one of the lamp sockets into and out of electrical connection with the plug. 60

Figure 8 is a cross sectional view taken on the line 8—8 of Figure 7.

Figure 9 is a perspective view of the disassembled parts of a switch for placing one of the sockets into and out of electrical connection with the plug; and 65

Figure 10 is a plan view of the lamp socket member. 70

Similar characters of reference designate like parts throughout the different views of the drawings.

In the embodiment of the invention shown in the drawings a pair of metallic threaded 75 lamp receiving shells 11, 11', each shell being arranged at the inner end with an annular flange or lug 12 and secured together in electrical connection in angular relation to each other by stamping a lip from the flanges 12, 80 bending the same laterally and securing such lips in juxtaposed relation by soldering or otherwise, as shown at 13 in Figure 6.

With the shells 11, 11' in the condition shown in Figure 6 a body of insulating material 14 is molded about said shells to surround and encase the same with the electrical connection 13 of the shells imbedded in said material, and the shells retained in fixed and angular relation to each other. The material 14 is formed with a recessed portion or pocket 15 arranging the body with three branches in two of which the shells 11, 11' are carried, said portion 15 having an opening 16 preferably in line with one of the sockets. Openings 17 are arranged in a separating wall between the recess and ends of the lamp sockets and located centrally of the sockets with the end of the openings in the socket having enlargements 18, and in which openings ter- 100

minal contacts 19 to constitute end or central contacts for the sockets are mounted to be carried by and insulated from the shells by the insulating material 14.

5 The contacts 19 comprise a metallic plate arranged with a perforation 20 for the engagement of a screw or rivet 21 passing through the openings 17 and secured within the recess portion 15 with electrical connection means. The contact plate is bent with the portion having the perforation 20 engaging in the enlargement of the opening 17 and when secured in position the other end is bent to overhang the perforated portion, as shown 10 at 21' in Figure 6^a, to serve as a resilient contact maker to be engaged by the end contact of an electric translating device, such as a lamp 1.

To arrange the lamp sockets as an adaptor 20 for connection to a cutout in an electric circuit an electric connection plug is connected to the socket encasing material 14 in electrical connection with the sockets. The plug is shown of the type for connection to a threaded lamp 25 receiving socket and includes a block or button of insulating material 24 arranged with the usual outer and central feed or plug contact terminals comprising a threaded metallic shell 22 encircling the block and having the 30 outer end flanged and spun over a shoulder on said block, as shown in Figure 2, and a central contact 23 extending through a bore centrally of the block. The plug engages an annular seat or shoulder 25 arranged at 35 the opening to the recess 15 in the socket encasing material and secured therein and to the socket encasing material by tie members, shown in the form of bolts or screws 26 passing through the plug and perforations 40 in ears or lugs 27 extending inwardly from the plug shell 22 to engage in recesses 28 in the end of the plug below the heads of the bolts to electrically connect the bolts and shell. The bolts extend through the recess 45 15, perforations in the wall of the insulating material between the recess 15 and end of one socket, and through the flange or lug 12 of said socket shell and retained therein in electrical connection with said socket shell by 50 threading into metallic pieces or conductors 29 at the inner side of the flange, as shown in Figure 3, or said bolts may be threaded directly into the socket shell flange 12.

To electrically connect the center contacts 55 of the lamp sockets and plugs or button the center contacts of the sockets are connected to a conductor block 30 in the form of a plate bent to conform to the shape and lie contiguous to the wall of the recess 15 with a portion 60 extending across the opening of the recess and the plug. The end contact 23 of the plug is arranged as a bolt or screw with the head of the bolt countersunk into the block 24 to constitute a contact terminal, the bolt passing 65 through the block and having threaded con-

nection with the conductor 30 in the recess 15 of the encasing material, as shown in Figure 2.

By the foregoing described arrangement of plug and lamp sockets the insulating and encasing material of the socket shells may be readily molded in an integral one piece structure and the end or central terminal contacts of the lamp sockets may be readily applied thereto and the plug or button separately connected thereto in electrical connection with the lamp socket contacts.

To adapt and support a shade from the lamp sockets the encasing material as it is molded is arranged with attaching means in the form of external threads or grooves molded in and consisting of said material, as shown at 31.

To place one of the lamp sockets into and out of circuit with the plug switch mechanism is provided within the recessed portion 15 of the encasing material as shown in Figures 7 and 8. For this purpose the end contact of one lamp socket is connected permanently to the conductor member 30, said conductor extending only to the point 32, Figure 7. A contact member 33 extends laterally in the recess 15 from and in electrical connection with the center contact of the lamp socket 11. To place said lamp socket into and out of electrical connection with the plug contacts, a contact or circuit maker and breaker 34 (Figure 9) is rotatably mounted on a post 35 extended from the center contact of the socket 11, as shown at 35 in Figure 7. This contact maker has a pair of opposite fingers 36 to be placed into and out of contact with the contact member 33 and the portion 32 of the conductor 30 and thereby place the center contact of socket 11 into and out of electrical connection with the center contact of the plug. To actuate the contact maker a disk of insulating material 37, Figure 9, is rotatably mounted on the post 35 having a plate 38 fixed thereto by rivets passing through perforations in said disk and plate, the plate being arranged with lips or nibs 39 to extend laterally from the disk and adapted to engage with nibs 40 extending oppositely from the contact maker 34 as rotative movement is imparted to the disk and plate in one direction and thereby rotate the contact maker. To operatively connect and disconnect the plate with the contact maker the disk and plate are urged axially in a direction toward the socket 11 with the contact maker fingers in yielding engagement with the contact members 32, 33 by a spring 41 coiled about the post 35 and confined between the disk 37 and a head at the end of said post. The contact maker is actuated by a chain or cord 42 connected to a slot 43 formed at one end of the juncture of a flange 44 with said disk, said actuator passing through an opening 45 in the wall of the recess portion 15 of the socket encasing ma-

terial. By the alternate movement of the disk 37 the contact is caused to alternately engage with the contact plates 32, 33 and the insulating material between said contacts; and to retain the contact maker in its adjusted 5 position the contact fingers 36 may be arranged as detents to engage recesses in the contacts 32, 33 and the encasing material, or the insulating material may be provided 10 with circularly arranged cam portions 46 as shown in Figure 10, with the contacts 32, 33 arranged on opposite cam portions, the shoulders 47 of said cam portions preventing retrograde movement of the contact maker.

One end of the spring 41 is connected to 15 the disk 37 and the opposite end to the post 35, the tension of the spring being such as to urge the actuating disk 37 in one direction to retain it in a predetermined position, and as the disk is rotated by the actuator 42 it 20 will be moved from such position in a direction opposite to that in which the spring tends to move the disk, such movement being limited by the connection of the actuator chain 25 coming opposite to the opening 45 when any further pull on the chain will be in a direction radially of the disk and no further movement imparted to the disk.

It will be obvious that the switch mechanism may be arranged whereby instead of 30 controlling the opening and closing of the circuit for one of the lamp sockets only, such switch will be adapted to open and close the circuit for either one or all of the lamp 35 sockets.

Having thus described my invention I claim:

1. In a lamp socket cluster, electrically connected lamp receiving shells, a molded one 40 piece body of insulated material with the shells encased by and in embedded relation thereto uniting the shells and insulator body in an integral rigid structure, said insulator body having a recess molded therein at the 45 inner ends of the shells with a wall of the insulating material interposed between said recess and the inner ends of the shells and having perforations therethrough centrally of the shells, contact terminals carried in said 50 perforations exposed centrally of and in insulated relation to the shells, a connection plug embodying a block of insulating material having a bore therethrough and a threaded shell contact terminal encircling the same, 55 tie members of conducting material extended through the insulator block of the plug and the wall of the insulating material of the body between the recess and one lamp receiving socket to unite the plug with the insulator 60 body and electrically connect the shell of said latter socket and the shell contact terminal of the plug; a plate of conducting material electrically connecting the central contact terminals of the socket shells within the recess in the insulator body, a headed bolt ex-

tended through the bore of the plug to constitute the center contact thereof and having threaded connection with said plate, and the insulator body at the outer end of the shells having external shade supporting threads 70

2. In an electric connection device, a one piece molded insulator body arranged with recesses opening outward therefrom with a perforation in the separating wall of the recesses and having a metallic shell contact terminal in one recess and encased by and in embedded relation to the insulator material to serve as a lamp receiving socket and having the inner end flanged inwardly, a contact terminal centrally of said latter shell receiving recess and mounted in the perforation in the wall between the recesses, said terminal being exposed to the interior of the recess and constituting the end contact terminal for the 80 socket shell, a connection plug embodying a block of insulating material having a shell contact terminal encircling the same with a portion of one end flanged over an end of the block and a contact terminal extended centrally therethrough, said plug being adapted to be seated at the opening to the other recess to arrange said recess as a closed chamber, headed screws extended through the insulator block of the plug and insulator body and the shell flanges to unite the plug with said insulator body and electrically connect the shell contact terminals of the plug and socket, and a plate connected with the center contact terminal within the one recess and adapted for the electrical connection of the center contact of the plug. 95

3. An electric connection device as claimed in claim 2, wherein the insulator body at the outer end of the socket shell carrying recess of the insulator body is arranged with external threads molded therein for the removable connection and supporting of a shade from the insulator body. 105

4. In an electric connection device, a one piece molded insulator body having a pair of angularly arranged branches having recesses opening outwardly therefrom and a recess in and opening outward from the insulator body at the juncture of the branches with a perforation in the separating wall between said recess in the body and the recesses in the branches, electrically connected metal lamp receiving shell contacts in the branch recesses, a contact terminal mounted in the 115 perforations in the separating wall between the recesses to serve as center contacts for the lamp receiving contact shells, a connection plug embodying a block of insulating material having a shell contact encircling the same and a contact member extended centrally therethrough, said plug being adapted to be seated on the insulator body at the opening to the recess therein, screws extended through 120 the insulator block of the plug and the sep- 125

arating wall between the recesses in the body and one branch to secure the plug to the insulator body and electrically connect the shell contact thereof with the shell contact in one branch recess and arrange the recess in the insulator body as a closed chamber, a conductor block within said chamber to electrically connect the center contacts of the plug and one of the socket shells, a switch mechanism arranged in said chamber and operative from the exterior of the device to co-operate with said conductor block and the center contact of the other socket shell to open and close the circuit between the same.

5. An electric connection device as claimed in claim 2, wherein the insulator body is provided with a pair of lamp receiving socket shell carrying recesses arranged in angular relation to each other and the shells therein electrically connected, the screws to releasably connect the plug with the insulator body being operative to electrically connect the shell contact terminal of one lamp receiving socket with the shell contact terminal of the plug, and the insulator body at the outer end of both socket shell carrying recesses arranged with external threads molded therein for the removable mounting and supporting of shades from the insulator body.

6. In a combined plug and light device, a body member of insulating material having oppositely disposed recesses therein, a plug member including a button of insulating material and a threaded shell contact embracing the same and flanged over a shoulder adjacent the outer end of the button, said plug member embracing the entrance to one of said recesses and arranging said recess as a closed chamber, a threaded shell contact enclosed in the other recess, screws extended through the insulator body electrically connecting said shells, a central contact in the shell engaging recess, a block of conducting material in the other recess to which the central contact is electrically connected, and a screw extended through the button of the plug member having threaded connection with the conductor block for electrical connection therewith and forming a central contact at the end of the button.

7. In an electric connection device, a one piece insulator body arranged with recesses opening outwardly and oppositely therefrom, a metallic shell contact engaged in one recess and entirely enclosed by the recess wall to constitute a lamp receiving socket, said shell having the inner end flanged inwardly, a contact mounted in the wall between the recesses exposed to the interior of the shell carrying recess to constitute the center contact for said socket shell, a connection plug embodying a block of insulating material having an encircling shell contact with one end flanged over the outer end of the plug and a central contact extended through and

seated in the outer end of the block, said plug being secured to the insulator body at the outer end of the recess extending opposite to the shell enclosing recess and arranging said recess as a closed chamber, tie members 70 extended through the insulator block of the plug and separating wall between the recesses and the flanges of the shell contacts to releasably connect the plug to the insulator body and electrically connect the shell contacts, a contact piece connected with the center contact of the plug within the chamber, a contact maker movably mounted in the chamber to co-operate with said contact making piece and center contact of the shell to open and close the circuit between the plug and socket shell contacts, and means connected with said contact maker extended through an orifice in the wall of the chamber for actuating said contact maker exterior of 80 the device.

8. In a plug and socket device, a molded body of insulator material having a pocket and a socket opening oppositely therefrom with a wall of the insulator body separating 90 the pocket from the socket, a threaded shell contact enclosed in the socket having an in-turned flange at the inner end, a plug member embracing the opening to the pocket embodying a button of insulating material and a 95 threaded shell contact encircling said button, said shell contact having inturned lugs flanged over a shoulder adjacent the outer end of said button, screws extended through said inturned lugs of the button embracing the shell contact and flange of the other shell contact to electrically connect the plug and socket shells and operating to secure the plug member to the insulator body, a conductor member in the pocket, a contact mounted in 100 an opening in the separating wall between the pocket and socket exposed centrally of the socket connected to the conductor member in the pocket for electrical connection therewith, and a screw extended through the button of the plug member having threaded connection with the conductor member in the pocket for electrical connection therewith and forming a center contact at the end of 105 the button.

9. In a device of the character specified, an insulating body member having three branches, one of said branches having a pocket leading from the end thereof and the other branches having sockets and a wall of the insulator body separating the pocket from the sockets, a conductor member in the pocket, center contacts for the sockets, means passing through the center contacts, the separating wall and the conductor member to 120 secure said contacts in electrical connection to said wall, an insulator button embraced by an externally threaded shell contact having inwardly extending lugs flanged over a shoulder at the outer end of the button and 125 130

said button mounted at the entrance to said pocket, and a conductor member extended through said button and threaded into the conductor member in the pocket for electric connection therewith, screw shell contacts mounted in the sockets having inwardly extending flanges at the inner ends, screws passing through the lugs of the thread-contact embracing the button and one of the socket shell contacts and having threaded connection with conductors engaging with the flange of said latter screw shell contact to secure the button to the insulator body and forming electrical connection between said contact shells, and means for electrically connecting the shell contacts in the sockets.

Signed at the city of New York, in the county of New York and State of New York, this 10th day of December, 1921.
